UNITED STATES PATENT OFFICE

JOSEPH SVOBODA, JR., OF RACINE, WISCONSIN, ASSIGNOR TO BELLE CITY MALLEABLE IRON COMPANY, OF RACINE, WISCONSIN, A CORPORATION OF WISCONSIN

LATCH FOR A MOLDER'S FLASK

Application filed November 3, 1930. Serial No. 492,953.

This invention relates to a latch for a molder's flask and especially for the so called snap flasks which have a hinge at one corner and a separable latch at a diagonally opposite corner whereby the flask sides may be removed laterally to free a mold without disturbing the sand.

The object of the invention is to provide a simple, inexpensive latch capable of effectively and firmly holding the sides of the flask together to form a rigid corner.

Another object is to interlock the parts of the latch in a special manner to produce the rigid corner mentioned.

Other objects will be apparent to those skilled in this art as the disclosure is more fully made.

Briefly such desirable objects may be achieved by the form of the invention shown in the accompanying sheet of drawings by way of example, wherein the latch comprises two main, right angularly disposed latch parts carried by the flask sides, said two parts being interlocked and tightly clamped together by a third part comprising a pivoted wedge member. So much will suffice for the present, and in the meanwhile reference should be made to the figures of drawings in which:

Figure 1 is a top plan, assembled view of the flask corner and latch;

Figure 2 is a side view of the latch as viewed from the right to the left in Figure 1;

Figure 3 is a side view of the latch looking at the other side shown in Figure 1;

Figure 4 is a horizontal sectional view of a detail as seen along the line 4-4 appearing in Figure 3;

Figure 5 is a top view of one of the latch parts;

Figure 6 is a side elevational view of the same latch part as shown in Figure 5;

Figure 7 is an end view of a washer; and,

Figure 8 is a face view of the same washer.

Two sides of a conventional hinged flask are shown at 10 and 11 which are adapted to meet and form a closed corner of the flask as appears in Figure 1.

A first latch part 12 is suitably secured to

the outside surface of the flask side 10, said part 12 widening out where it crosses the end of side 11, said widened portion appearing at 13 and terminating in a vertical, tapered edge 14 which projects laterally of the end of side 11 as shown in Figure 1. Midway between its top and bottom edges this edge 14 is formed with a notch 14' for a purpose later to appear. The narrow portion of this first latch part 12 has integrally formed thereon a circular boss 15 having two diametrically arranged notches 16 formed therein, for a purpose soon to appear.

A wedge latch member 17 is next provided the same having at one end a large opening 65 whereby to mount said member 17 pivotally on the boss 15. A washer 18 is also provided to hold the member 17 on its boss 15, there being a screw 19 to secure all of said parts as a unit assembly with the part 12 to the side 70 10 as indicated best in Figure 4. Incidentally, the washer 18 carries two diametrically disposed lugs 19 which fit into the notches 16 heretofore described and as a result the washer 18 is held against turning movement 75 when the member 17 is pivoted. To permit free pivoting from the member 17 it is best that the thickness of the part 17 be somewhat less than the thickness of the boss 15 whereby to provide the required clearance as best appears in Figure 4. The part 17 is bent back 80 slightly as shown in Figure 1 and terminates in a hook 20 having a finger grip portion 21.

A second latch part 22 is securely fastened to the flask side 11 said part having a vertical shoulder 23 flush with the end of side 11, said part 22 adjacent said shoulder carrying an integrally formed curled lip 24 forming a vertical socket that receives the tapered 85 edge 14 of the part 12. The part 22 also includes a projected hook part 25 which is designed to cooperate with the hook 20 to wedge parts 12 and 22 together. The extension which becomes hook 25 of part 22 it is 90 of interest to note will seat in the notch 14' of the part 12.

In clamping the two flask sides together to form a rigid corner as shown in Figure 1 the two sides are brought together. In do- 100

ing this the edge 14 of part 12 seats in the vertical socket provided by the curled lip 24 in part 22. Still further the extension 25 of part 22 fits into and seats in the notch 14' of the part 12. Thus, a double interlock is provided between the two main latch parts 12 and 22. Next the pivot member 17 is swung downwardly to cause the hook 20 to ride across the hook extension 25 which wedges the interlocking portions on parts 12 and 22 very tightly and securely together to form a solid, rigid corner for the flask. Thus the sides 10 and 11 of the flask are held against all lateral movement as well as any up and down movement.

From this disclosure it will now be appreciated that a secure, interlocked latch is provided which firmly clamps the flask side sections together and so holds them during the sand ramming operation, said latch however permitting ready release of the sections when the mold is to be removed.

It is now apparent that a simple and fool-proof latch is provided which achieves the desirable objects heretofore recited. It is to be particularly understood that this latch may be employed elsewhere than in connection with flasks as herein disclosed and that it is the intention to cover all changes and modifications which do not materially depart from the spirit and scope of the invention, which has been defined in the following claims.

What is claimed is:

1. The combination with the adjacent sides of a flask, of a latch to form a rigid corner lock for the sides, said latch comprising a first part secured to one side, said first part terminating in a projected straight vertical edge, said part also including a notch, a second part secured to the other side which part includes a curled lip to provide a vertical socket to receive the vertical edge of the first part and an extension to fit in the notch of the first part, whereby to interlock said two parts against relative movement, and means to draw and latch said parts together.

2. The combination with the adjacent sides of a flask, of a latch to form a rigid corner lock for the sides, said latch comprising a first part lying flatly against a side and secured thereto, said first part terminating in a tapered vertical edge which projects beyond the other side of the flask, said first part also including a notch, a second part secured to the other side of the flask, and having an outwardly curled lip to provide a vertical groove throughout its width having a taper wedgingly to receive the tapered edge of the first part, said second part having an extension to fit the notch in the first part and also having at its free end a hook portion, a bearing boss provided on the first member, and a latch member journaled on said bearing including a bowed out portion to clear the

aforementioned curled lip, said latch member terminating in a hook to cooperate with the first mentioned hook in drawing the parts securely together.

3. The combination with the adjacent sides of a flask, of a latch structure to form a rigid corner lock for the sides, said latch structure comprising a first part lying flatly against a side of the flask and secured thereto, said first part terminating in a tapered vertical straight edge which projects beyond the adjacent side of the flask, said first part having a notch formed in said straight edge between its ends, a second part similarly secured to the adjacent flask side and having an outwardly curled lip to provide a vertical groove formed complementarily wedgingly to receive the straight edge of said first part, said second part including an extension to fit in the notch aforementioned, said second part at its free extended end terminating in a hook portion, a latch member pivotally carried alongside said first part and provided with an outwardly bowed portion to clear the curled lip, and said latch member adapted to wedgingly lock with the hook portion to clamp all of the interlocking portions of the latch structure securely together.
